US00D888726S

(12) **United States Design Patent** (10) Patent No.: **US D888,726 S**
(45) Date of Patent: ** *Jun. 30, 2020

(54) **DISPLAY SCREEN OR PORTION THEREOF WITH A GRAPHICAL USER INTERFACE**

(71) Applicant: **BEIJING KUAIMAJIABIAN TECHNOLOGY CO., LTD.**, Beijing (CN)

(72) Inventor: **Jun Yan**, Beijing (CN)

(73) Assignee: **BEIJING KUAIMAJIABIAN TECHNOLOGY CO., LTD.**, Beijing (CN)

(*) Notice: This patent is subject to a terminal disclaimer.

(**) Term: **15 Years**

(21) Appl. No.: **29/663,838**

(22) Filed: **Sep. 19, 2018**

(30) **Foreign Application Priority Data**

Mar. 21, 2018 (CN) 2018 3 0105172

(51) LOC (12) Cl. **14-04**

(52) U.S. Cl.

USPC **D14/485**

CLAIM

I claim the ornamental design for a display screen or portion thereof with a graphical user interface, as shown and described.

DESCRIPTION

The FIGURE is a front view of a display screen or portion thereof with a graphical user interface showing our new design.

The broken lines shown in the FIGURE represent portions of the display screen or portion thereof with a graphical user interface that form no part of the claimed design.
